CLAIM

I claim the ornamental design for a positioning tool, substantially as shown and described.

DESCRIPTION

FIG. 1 is a perspective view of a positioning tool embodying my design.

FIG. 2 is a side elevational view thereof with the opposite side being a mirror image.

FIG. 3 is a bottom plan view thereof as viewed from the left in FIG. 1.

FIG. 4 is a top plan view thereof as viewed from the right in FIG. 1; and,

FIG. 5 is an end elevational view thereof as viewed from the right in FIG. 2 with the opposite end being a mirror image.
